UNITED STATES PATENT OFFICE.

COLLIER MONROE, OF WACO, TEXAS.

HAIR CLIPPER.

1,416,115.

Specification of Letters Patent. Patented May 16, 1922.

Application filed May 16, 1921. Serial No. 469,842.

To all whom it may concern:

Be it known that I, COLLIER MONROE, a citizen of the United States, residing at Waco, in the county of McLennan and State 5 of Texas, have invented certain new and useful Improvements in Hair Clippers, of which the following is a specification.

This invention relates to new and useful improvements in hair clippers.

10 The object of the invention is to eliminate vibration and to transmit to the operating lever and cutter blade, a maximum power, thus making for a reduction of lost motion. Another object of the invention is to simplify the construction and produce a clipper 15 more easily handled and more efficient in its work.

In carrying out the invention a volute or spiral driving gear is employed to drive 20 the gear which swings the operating lever. It will be noted that the spiral driving member engages said gear at a central position with relation to the swing of the lever, whereby a constant driving relation is maintained and compensation for wear is had. 25 Also the tension plate has contact with the blade entirely across its front end which reduces wear and is superior to the lugs commonly used. A further feature of the invention is the elimination of packing strips adjacent 30 the pivot post of the operating lever.

A construction designed to carry out the invention will be hereinafter described together with other features of the invention.

35 The invention will be more readily understood from a reading of the following specification and by reference to the accompanying drawings, in which an example of the invention is shown and wherein:

40 Fig. 1 is a plan view of a device constructed in accordance with my invention,

Fig. 2 is a side elevation of the same,

Fig. 3 is a plan view of the device with the cover and tension plates removed and a 45 portion in section,

Fig. 4 is a longitudinal vertical sectional view,

Fig. 5 is a face view of the volute gear disk,

50 Fig. 6 is a detail showing the engagement between the gear disk and the gear, said gear disk being shown in section along the lines 6-6 of Fig. 5.

In the drawings the numeral 10 designates 55 a casing having a reduced shank 11 at its

rear end. The forward end of the casing is inclined and a cutter blade 12 is suitably fastened thereto. At the forward end of the casing a transverse bridge 13 is provided and receives an upright pivot stud 14 which is 60 screw thereto and also has its upper end screw threaded. Inwardly directed flanges 15 are provided along the front edge of the bridge.

The fixed cutter blade 12 is provided with 65 the usual upstanding rectangular lugs 16 which are received in the rectangular slots 17 of the usual reciprocating blade 18. The blade 18 has a central notch 19 in its rear edge which is adapted to receive the arm 20 70 on the front end of an operating lever 21 which latter is pivoted on the stud 14 and supported on the bridge 13. The lever 21 has a segment 22 from which the arm 20 extends. This segment is disposed forwardly 75 of the stud and is arranged to swing between the curved ends of the flanges 15. By this arrangement packing strips are eliminated and a more practical construction had. The reciprocating blade 18 is mounted on the 80 blade 12 in the usual manner and is adapted to be reciprocated when the lever 21 is swung.

The lever 21 has a central longitudinal slot 23 in its rear end receiving a slide block 85 24 which is confined on an eccentric pin 25 carried on the upper side of a gear wheel 26. The gear wheel 26 is supported on a stud 27 mounted in the bottom of the casing 10. In the shank 11 I dispose longitudinally of the 90 device, a shaft 28 which is provided with a circumferential groove 29 receiving the end of a set screw 30 whereby said shaft is held against longitudinal displacement. The rear end of the shaft projects into a counter bore 95 31 and is adapted to be connected with a flexible shaft (not shown) which is driven by an electric motor or any other means. The screw 30 also fastens a spring latch 32 which overhangs the counter bore 31 for 100 holding the flexible shaft therein.

It has been customary to drive the gear wheel 26 in clippers of this type, by means of a worm. Such driving mechanism produces considerable vibration and this vibration 105 causes the cutter blade to skip, so that the hair is not cut during these skips and the clipper does not do first class work. The worm gear drive soon wears and this aggravates the vibration. Further it is necessary 110

to operate the worm drive at a much higher rate of speed than is contemplated with the present invention. On the inner or forward end of the shaft 28 I mount a volute gear 5 disk 33 which has on its face a spiral or volute driving member 34. The disk is placed substantially tangentially to the gear 26 and the outer end of the spiral member 34 is reduced so as to more readily enter between the teeth of the gear wheel. It will be seen that the outer end of the spiral member engages with the teeth on a line which substantially registers with the central position of the lever 21. This point of engagement is substantially in alignment with the pivot points of the lever and the gear 26 and it will be seen that when the block 24 reaches either end of its stroke it will also be aligned with said pivot points and the volute gear 20 will be exerting its force on the gear 26 at right angles to this alignment, consequently there will be no tendency on the part of the block and lever to bind and a much smoother operating device will be had. It is pointed 25 out that wear will have little or no effect upon the transmission of motion to the gear wheel 26.

The upper side of the casing is reduced to receive a flat cover plate 35 conforming 30 to the contour thereof and penetrated by the stud 14. This cover plate has an upset portion 36 over the disk 33. I also provide a tension plate 37 which overhangs the sides of the casing at the front end thereof and 35 has its rear end resting on the cover plate. The tension plate has its front edge 38 contacting with the blade 18 throughout its length whereby it exerts an even pressure on said blade and holds it in the desired 40 relation with the blade 12. The stud 14 penetrates the plate 37 and receives a coiled spring 39 between the plates which spring acts to hold the cover plate 35 in place and to support the tension plate 37. A tension 45 spring 40 is mounted on the stud and bears on the plate 37. The tension spring is confined by a nut 41 screwed on the upper end of the stud 14. By adjusting this nut the pressure of the plate 37 on the blade 18 is 50 regulated.

It will be seen that by having the tension plate engaging entirely across its front edge with the blade 18, cut hairs will not have as much tendency to work under said plate 55 and a more ample bearing surface will be had. It is customary to form the front edge of the tension plate with a pair of small lugs which bear on the reciprocating blade. These lugs soon wear and the device ceases 60 to function properly. As a matter of convenience the casing 10 is indented on each side at 42 and the rear end of the plate 37 is contracted as well as curved, whereby the device is more easily grasped and held in 65 the hand of the operator. The shank is pro-

vided with a slot 43 so that the clipper may be supported when not in use by hanging it on a suitable projection.

Various changes in the size and the shape as well as modifications may be made, without departing from the spirit of the invention. 70

What I claim is:

1. In a hair clipping device, a casing, a cutter blade carried by the forward end 75 of the casing, a reciprocating cutter blade coacting with the first named cutter blade, a gear arranged within the casing, a lever pivotally mounted within the casing to swing in a plane approximately parallel with the plane of rotation of the gear, said lever having its forward end connected with the reciprocating cutter and its rear end extending over one side of the gear and terminating at a point inwardly of the rear portion of the gear, means connecting the lever and gear, a gear-disk mounted within the casing rearwardly of the gear and having its plane of rotation at substantially a right angle to the plane of rotation of said gear, 80 said gear-disk being provided upon its forward side with a curved drive rib for engaging the teeth of said gear, said gear-disk extending laterally beyond the gear and being free from engagement with the rear end of said lever, and a shaft carrying the gear-disk and journaled in the rear portion of the casing: 85

2. In a hair clipping device, a casing, a cutter blade carried by the forward end of 90 the casing, a reciprocating cutter blade coacting with the first named cutter blade, a gear arranged within the casing, a lever pivotally mounted within the casing to swing in a plane approximately parallel 100 with the plane of rotation of the gear, said lever having its forward end connected with the reciprocating cutter and its rear end extending over one side of the gear and terminating at a point inwardly of the rear portion of the gear, means connecting the lever and gear, a gear-disk mounted within the casing rearwardly of the gear and having 105 its plane of rotation at substantially a right angle to the plane of rotation of said gear, said gear-disk being provided upon its forward side with a curved drive rib for engaging the teeth of said gear, said gear-disk extending laterally beyond the gear and being free from engagement with the rear end of said lever, and a shaft carrying 110 the gear-disk and journaled in the rear portion of the casing: 115

3. In a hair clipping device, a casing, said 120

casing having its side walls pressed inwardly providing exterior recesses for the reception of the fingers of the operator, a cutter blade carried by the forward end of the casing in advance of said recesses, a reciprocating cutter blade coacting with the first named cutter blade, a gear arranged within the casing rearwardly of said exterior recesses, a lever pivotally mounted within the casing to swing in a plane approximately parallel with the plane of rotation of the gear, said lever having its forward end connected with the reciprocating cutter and its rear end extending over one side of the gear and terminating at a point inwardly of the rear portion of said gear, means connecting the lever and gear, a shaft

extending longitudinally of the casing with its forward end projecting into the interior of the casing, said shaft being arranged wholly rearwardly of said gear, a gear-disk mounted upon the forward end of said shaft and rearwardly of said gear and having its plane of rotation at substantially a right angle to the plane of rotation of said gear, said gear-disk being provided upon its forward side with a curved drive rib for engaging the teeth of said gear, said gear-disk extending laterally beyond the gear and being free from engagement with the rear end of said lever.

In testimony whereof I affix my signature.

COLLIER MONROE.
